THERMAL RESPONSIVE DEVICE

Clifford Hotchkiss, Milwaukee, Wis., assignor to
 Perfex Corporation, Milwaukee, Wis., a corpora-
 tion of Wisconsin

Application October 30, 1940, Serial No. 363,521

18 Claims. (Cl. 200—137)

This invention relates in general to thermal responsive devices but more particularly to a thermal device adapted for operation as a safety control for burners and the principal object of the invention is to provide a new and improved type of thermal device for the aforesaid purpose which is simple in construction, reliable in operation and which will withstand rugged usage and high temperatures without deterioration or failure to function properly.

In the automatic operation of burners for furnaces it is desirable that some provision be made for quickly stopping the operation of the burner in the event of combustion failure during the running period, or ignition failure upon starting, in order that hazardous conditions may be obviated.

It is an object of the invention to provide an improved combustion responsive and heat sensitive device for controlling the operation of a burner in which the thermal element is responsive to radiant heat or energy emanating from the furnace combustion chamber.

In the past, it has been common to form radiant heat operated combustion responsive devices of a diaphragm exposed to radiant heat from the flame and restrained from expanding at its edges, the diaphragm thus buckling upon the presence of combustion and unbuckling when combustion ceases. Usually such diaphragms operate a combustion switch through a slip friction mechanism of some sort. One disadvantage of such arrangements is that they are under some conditions too responsive said often cause opening and closing of the combustion switch when the burner is first started, even though a real flame failure does not occur. One cause for this is a shifting in position of the burner flame as the combustion chamber warms up. Thus when the burner is first started the flame may be near the control while later, due to increased draft caused by heating of the chimney, the flame may move to a different position.

It is an object of this invention to provide a thermal responsive arrangement of this general type with means compensating for the unstable nature of the flame when the burner is first started.

In accordance with my invention, the responsive device is formed of a diaphragm and a ring attached to the edges thereto. Both the diaphragm and ring are equally subjected to the radiant heat and the diaphragm is formed of a material having a high coefficient of expansion while the ring is formed of an expansive material having a lower coefficient of expansion. By making the ring of expansive material, the degree of buckling of the diaphragm may be reduced, so that the bulge of the diaphragm is

relatively small, thereby making it more sensitive to reversals in temperature. This constitutes a further object of the invention.

When a device of this character is used on 5 certain types of burners, or under certain conditions, the diaphragm may rise in temperature at a rate considerably faster than the ring. When the ring and diaphragm begin equalizing in temperature, the diaphragm may unbuckle 10 causing reverse movement of the combustion switch even though no flame failure has occurred. This reverse action of the diaphragm however is compensated for by the present invention.

15 It is accordingly another object of this invention to provide a thermal responsive device having a pair of elements which change in temperature at different rates with means for preventing reversals in operation due to unequal 20 rates of heating.

A further object is to provide an improved combustion responsive device of the disc or diaphragm type, this device responding to the radiant heat from the furnace and operating a 25 switch through a slip friction mechanism, the latter mechanism serving to cause actuation of the switch immediately upon reversals in movement of the diaphragm, and permitting unrestricted diaphragm movement after the switch 30 is actuated.

A further object is to provide novel means for 35 adjustably supporting the thermal responsive device upon a furnace to provide for any variations in the intensity of the flame in the combustion chamber.

An additional object of the invention resides in the provision of means for shielding and protecting the thermal element from transient drafts of air in the furnace which may produce erratic 40 operation of the device.

Other objects and advantages of the improved 45 thermal device reside in certain novel features of construction, arrangement, and combination of the various elements which will be herein- 50 after more fully described, particularly pointed out in the appended claims, and illustrated in the accompanying drawing in which:

Fig. 1 shows a cross sectional side elevation 55 of the thermal responsive device and associated switching mechanism mounted on a burner tube;

Fig. 2 is a top view of the switching mechanism;

Fig. 3 is an end view of the thermal responsive device taken along the line 3—3 of Fig. 1;

Fig. 4 is an end view of a modified form of the thermal responsive device;

Fig. 5 is a cross sectional side view of Fig. 4;

Fig. 6 is a fragmentary view of a gun type of

burner installation on a furnace to which the invention is applied; while

Fig. 7 is a fragmentary view of a spinner type of burner to which the invention is applied.

The invention comprises generally the combination of a thermal responsive device indicated at 5 and a control device or switching mechanism associated therewith indicated at 6, both elements being arranged for example upon a burner as indicated in Fig. 6. The thermal responsive device 5 is arranged within an enclosing chamber or casing preferably in the form of a casting 7, having fairly thick walls including a flat bottom wall 8 through which a bolt 9 passes and is threaded into the side wall 10 of the blast tube of a burner for supporting the casting 7. A pair of downwardly projecting legs, one of which is shown at 11, straddle the tube 10 and serve to space the bottom wall 8 from direct thermal contact with the tube 10. The casing 7 has semi-circular side and top walls and is provided with an opening 12 in the front thereof. The upper portion of the wall extending toward the opening 12 is gradually sloped downward as indicated at 13. The opening 12 is arranged so as to face the combustion chamber of a furnace as shown in Fig. 6. The rear or opposite end of the casing 7 is arranged with a cylindrical wall 14 having a shoulder portion formed therein to provide a seat for a flat metal disc 15 which closes off the end of the casing 7 and lowers the transmission of heat through the casing 7 to the switching mechanism 6. This disc 15 also prevents the escape of the combustion gases through the thermal unit and prevents any drafts of air caused by the chimney drafts in the furnace from entering the thermal unit 5 and affecting the reliable operation of the unit.

The thermal responsive device 5 is supported within the casing 7 by means of a supporting tube 16 passing through an opening in the disc 15. An operating rod or shaft 17 passes axially through the tube 16 and projects outwardly from the front end thereof. The condition responsive or thermal operated device includes a relatively thin flat annular disc member or diaphragm 18 having a rearwardly projecting flange portion 19 formed thereon. The disc 18 is arranged at its front surface to receive and absorb radiant heat waves or energy emanating from the burner flame. These radiant heat waves pass through the opening 12 and impinge upon the front surface of the diaphragm 18. The diaphragm 18 is preferably constructed of material having a relatively high thermal coefficient of expansion. I have found the best results to be obtained by using .0000202 cms. per cm. per degree centigrade. This material may be stainless steel comprising 18 to 25% chromium and 8 to 12% nickel. It is bowed outward toward the opening 12 a slight amount as a result of a shoulder 20 on the shaft 17 engaging the same and applying a slight amount of pressure to the diaphragm. The shaft 17 as will be hereinafter pointed out is normally spring urged in a direction toward the diaphragm 18. Arranged upon the peripheral front edge of the diaphragm 18 is a confining means taking the shape of an annular ring 21 preferably made of a material having a somewhat smaller coefficient of heat expansion than the material of which the diaphragm 18 is constructed. I prefer to use a material for this ring having a coefficient of expansion of approximately .0000161 cms. per cm. 75

per degree centigrade. This part may be formed of "Inconel" comprising 78 to 80% nickel, 12 to 14% chromium and 6 to 8% iron. The ring 21 is thicker than the diaphragm and preferably spot welded at recurring intervals to the periphery of the diaphragm. The diaphragm 18 upon being subjected to elevated temperatures such as caused by radiant heat waves bows or bulges outward as indicated by the dotted lines in Fig. 1, while the annular ring 21 expands circumferentially at a somewhat slower rate than the diaphragm. The end of the shaft 17 loosely projects through a hole in the center of the diaphragm so as to guide and support the end of the shaft.

Rigidly secured to and arranged upon the front end of the supporting tube 16 is an annular flat metal disc 21a positioned directly behind the diaphragm 18. This disc 21a serves as a support for a plurality of bimetallic flat strips 22 illustrated more clearly in Fig. 3. The bimetal strips 22 are attached at one end by rivets as shown to the disc 21a. The opposite ends of the bimetal strips are provided with reduced portions 23 which project loosely through slots provided in the flange 19 of the diaphragm 18. In assembling the thermal responsive element upon the end of the supporting tube 16 one or more of the reduced portions 23 of the bimetal blades 22 are inserted in the corresponding slots in the flange 19 of diaphragm 18 and then each portion of the flange 19 between the remaining bimetal blades 22 is pressed inwardly so that the remaining projection 23 may be snapped into position in the associated slot. The bimetal blades 22 are thereby securely locked in position so as to support the diaphragm 18 upon the end of the shaft 17. The bimetal strips are each so constituted that upon a temperature rise they will bow their free ends in the direction indicated by the arrows in Fig. 1 so as to move the diaphragm 18 outwardly for a purpose which will be hereinafter pointed out. It will be noted that the bimetal strips 22 being arranged behind the diaphragm 18 are shielded by the diaphragm from direct contact with the radiant heat waves passing through the opening 12. The bimetal strips 22 therefore are activated as the result of the heat transmitted by conduction from the diaphragm through the flange 19 and by the convection from the rear surface of the diaphragm.

In order to prevent any cooling air currents from passing through the tube 16 to the rear side of the diaphragm 18 and also to the bimetal blades 22, an enclosing means is provided for closing the end of the tube 16. This enclosing means includes a washer 24 axially disposed upon the shaft 17 and covering the open end of the tube. A light spring 25 extends between the washer 24 and the shoulder 20 of the shaft 17 so as to at all times urge and hold the washer against the open end of the tube. This spring 25 is light enough so as to have no appreciable effect upon the operation of the diaphragm 18.

The control device which is actuated by the operation of the thermal responsive device 5 is shown, for example, in the form of a switch mechanism 6. This switching mechanism is suitably enclosed in a rectangular shaped metal casing or housing 26 which is supported by means of an angular U-shaped bracket 27 and screws 28 upon the top of the blast tube 10 of the burner. The bracket 27 comprises a pair of legs, one of which is shown, which straddle the tube 10 and have their lower ends bent to

conform to the cylindrical shape of the tube and are secured thereto by the screws 29. This screw 29 passes through a slot 30 of each bracket leg 27 so that the bracket and the switching mechanism 6 may be adjustably positioned longitudinally within certain limits along the surface of the blast tube 10. By means of this adjustment the element supporting tube 16 and the thermal device 5 may be laterally positioned within the casing 7 at any desired location either closer or further away from the opening 12 of the casing 6, depending upon the intensity of the burner flame within the combustion chamber so that the correct response of the thermal element may be more accurately and reliably gauged. In the case of a very hot fire the thermal device 5 would be positioned further away from the opening 12 whereas in the type of burner in which a lower flame would exist the thermal device 5 would be adjusted closer to the opening 12.

A sheet metal enclosing cover 31 is provided for protecting the switching mechanism 6. It is adjustably attached to the blast tube 10 by means of a screw 32 on each side riding in a slot 33 so that the cover 31 may be shifted whenever the switching mechanism is adjusted. The casing 26 is provided at one end with an opening in which a conduit connection or a rubber grommet 34 may be inserted as shown. This serves for the purpose of providing an entry for the electrical connecting wires 35. A cover plate 36 for enclosing the casing 26 is provided which is held on the casing by means of a screw 37. The screw 37 threads into a protecting plate 38 arranged immediately above the switching mechanism and which is secured to the sides of the casing 26 by means of screws 39, one of which is shown. A projecting edge of the plate 38 extends through an opening 40 in the side of the casing to further support the plate 38. The plate 38 thereby serves to protect a portion of the mechanism and likewise serves as a securing means for the screw 37. One side wall of the casing 26 has a threaded projecting portion 41 formed integral therewith and into which the end of tube 16 is threaded. A lock nut 42 threaded on the tube 16 and tightened against the side wall of the casing 26 rigidly secures and locks the thermal device 5 and the switching mechanism 6 in associated operative relationship. This threaded engagement provides a calibration or adjustment of the thermal device 5 within the casing 7 and of the switching mechanism. A compression spring 43 encircles the outside of the supporting tube 16 and exerts its force between the lock nut 42 and the rear of the shielding disc 15. The purpose of this spring 43 is to at all times hold and maintain the disc 15 in its set position upon the shoulder formed in the cylinder 14 of casing 7. The disc 15 will remain on its seat and close the end of casing 7 regardless of the position to which the switching mechanism 6 may be longitudinally shifted when an adjustment of the position of the thermal device 5 is made.

Arranged in spaced relation to the bottom wall of the switch casing 26 is a flat insulating plate 44, the general shape of which is shown in detail in Fig. 2. The plate 44 is supported by means of a number of bushings 45 riveted at one end to the bottom of casing 26 and screws 46 threading into the bushings.

The switching mechanism is preferably of the so-called "slip friction" type, that is, the contact

structure is operated immediately upon initial movement of the mechanism and upon continued progressive movement a slipping action takes place between the elements while the contacts remain closed. By this arrangement the contact mechanism is actuated immediately upon reversals of the switching mechanism caused by temperature changes. In the embodiment illustrated this switching mechanism is preferably of the type illustrated in the Homer E. Malone co-pending application, Serial No. 363,431, filed October 30, 1940, in which this structure is described in greater detail and claimed therein. The slip friction mechanism comprises generally a lever means including a pair of identically shaped and oppositely disposed lever arms 47 and 48 which are pivoted together for movement about the pivot pin 49 which is supported on the insulating plate 44. A second pivot pin 50 connecting the lever arms 47 and 48 together passes through a movable element or link 51. The link member 51 is adapted to freely rotate a limited amount about the pin 50 between the two lever arms and is provided with an axial bore into which the operating shaft 17 loosely projects. The lever arms 47 and 48 are connected together at one end by a pin 52 to which one end of a tension spring 53 is connected. The other end of spring 53 is connected to a supporting bracket 54 suitably secured to the bottom of the casing 26 as shown. The foregoing arrangement of elements is such that the spring 53 normally exerts a pull upon the lower end of levers 47 and 48 as viewed in Fig. 2 and tends to urge the lever arms about pivot pin 49 so that the link 51 transmits this spring force longitudinally to the operating shaft 17. The shaft 17 as a result urges its shoulder 20 against the rear side of diaphragm 18 thereby bulging it slightly outward at its center. From this arrangement it is seen that the diaphragm 18 upon being subjected to heat and as a result bowing outward permits the lever arms 47 and 48 to swing their upper ends in a clockwise direction as viewed in Fig. 2 and upon a drop in temperature affecting the diaphragm 18 the diaphragm forces the shaft 17 in a left hand direction to rotate the lever arms 47 and 48 clockwise against the action of the spring 53.

The slip friction mechanism proper includes a relatively thin steel blade 55 pivoted at one end to pin 49 and having a polished surface on both sides which is in intimate contact with a separate graphite disc 56 arranged on each side of the blade 55. Each graphite disc 56 is held in position on the blade 55 with tension by means of a thin spring blade 57 which is supported at each end in slotted openings in each lever 47 and 48. In order to adjust the degree of friction between the discs 56 and the blade 55, an adjusting screw 58 threads between the ends of the lever arms 47 and 48. By turning this screw the desired friction or compressive effort of the friction discs is obtained. The adjusting screw 58 is of sufficient length so as to serve as a stop for the lever arms by engaging the sides of a recess 59 formed in the insulating plate 44.

A switching arm 60 made of insulating material is secured to the friction plate 55 by means of rivets 61 as shown. The switch arm 60 at its free end carries a bracket arranged to support a movable contact 62 supported upon a thin press-back spring blade 62a as shown. The movable contact 62 is arranged in cooperative relationship with a fixed contact 63 which in turn is

carried upon an angular metal bracket 64 attached to the insulating plate 44 by screws such as 65. The bracket 64 has a slotted opening in its turned up portion through which a reduced portion 66 of the switch arm 60 projects. This slotted opening serves as a guide and slidable support for the end of the switch arm 60. An adjusting and stop screw 67 threaded through a projecting end of the bracket 64 is adapted to engage one edge of the switch arm 60 when the arm is in contact opening position. The adjusting screw 67 enables the switch arm to be adjusted to operate with any desired degree of movement. The bracket 64 is also provided with a terminal screw 68 to which one of the wires 35 is attached to establish a circuit path for the fixed contact 63. A second bracket 69 is supported as shown to the insulating plate 44 and carries a terminal screw 70 for attachment of the other connecting wire 35. The bracket 69 has a pig tail connection passing underneath the insulating plate 44 and connecting with the spring blade of the movable contact 62.

Figs. 4 and 5 disclose a modified form of the thermal responsive device of the invention. In this form a thin diaphragm 71 of the same general shape as the diaphragm 18 of Fig. 1 is provided with a peripheral flange 72 extending rearwardly therefrom. Upon the front of the diaphragm 71 there is suitably spot welded an annular ring 73 having angular projecting portions 74 and 75 formed thereon and projecting through adjacent openings in the diaphragm 71 and extending to the rear side thereof. The diaphragm 71 is made of a material having a relatively high thermal coefficient of expansion, and the annular ring 73 of material having a lower coefficient of expansion. In place of the plurality of bimetal blades 22 of Fig. 3, a single flat blade 76 is provided which is suitably supported and secured as at 77 to the end of the supporting tube 16. The bimetal blade 76 at its lower end is provided with a pair of oppositely disposed projections 78 which are arranged to loosely fit into associated slots so as to straddle the projecting portion 75 of ring 73. The other end of the bimetal blade 76 has a series of shoulders formed thereon including a tongue-shaped projection 79 which passes through an associated slot formed in the projecting portion 74 of ring 73. A washer 24 and retaining spring 25 close the opening of tube 16 in the same manner as in Fig. 1.

Operation

The combination control, including the thermal responsive device 5 and the switching mechanism 6, is arranged as a unitary structure supported as has been pointed out upon the sides of a cylindrical blast tube 10 of an oil burner installation 81 in the position indicated in Fig. 6. The unit is supported in such a manner that the opening 12 will be exposed and point into the combustion chamber of a furnace indicated generally at 82. The flame 83 produced by the operation of the burner 81 projects into the fire pot of the furnace in the general manner indicated and the opening 12 is so arranged that radiant heat emanating from the flame can pass through the opening 12 and impinge upon the front surface of the diaphragm 18. The diaphragm 18 is therefore so positioned in the assembly of the device as to be directly exposed to the temperature of the flame to which it is arranged to respond. Fig. 1 shows the 75

switching mechanism including contacts 62 and 63 in their closed or "cold" position and if the fire is now started by the burner 81 in the well known manner, and combustion produced in the furnace 82, the diaphragm 18 will rapidly become heated by radiant heat from the flame and tend to expand. Circumferential expansion of the diaphragm 18 is restricted because of its intimate association with the annular ring 21 which does not heat up as fast as the diaphragm and which also expands a lesser amount than the diaphragm even when heated to the same temperature as the diaphragm. As a result the center portion or apex of the diaphragm 18 bulges outwardly. This action takes place almost immediately in response to combustion conditions in the furnace because the diaphragm is constructed of relatively thin material and absorbs the heat immediately. The outward movement of the apex of the diaphragm 18 permits the shaft 17 to follow this movement due to the follow-up movement of the levers 47 and 48 caused by the tension of the coil spring 53. The spring 53 at all times maintains a relatively close intimate relationship between the levers 47 and 48, the rod 17 and the diaphragm 18 so that no lost motion can exist in the linkage. Upon the initial movement of the levers 47 and 48 about the pin 49 the friction blade 55 is caused to effect a movement also about pivot pin 49 by reason of the force exerted upon the blade by the friction discs 56 which carry the blade along when the levers are rotated. The switch arm 60 is thereby swung in a clockwise direction as viewed in Fig. 2 so that the normally closed contacts 62 and 63 are immediately opened.

The action of opening the contacts 62 and 63 produces a change in the circuit operating conditions of the oil burner 81 in a manner well understood in the art for permitting the burner to continue to operate.

As the operating arm 60 rotates in a clockwise direction after opening the contacts 62 and 63 it encounters the adjustable stop screw 67. When this point is reached further rotation of the switch arm 60 and the friction blade 55 is halted and the contacts remain in their open position. The diaphragm 18 however may continue to buckle outward as a consequence of greater elevated temperatures to which it may be subjected as the flame in the combustion chamber acquires greater intensity. As a result the spring 53 continues to exert a pivoting movement of the lever arms 47 and 48 about pivot pin 49. The friction blocks 56 on each side of friction blade 55 can now frictionally slip across the surface of the blade 55 without causing further motion of the blade 55 and without straining any of the mechanism.

When the burner is first started up, the combustion chamber is relatively cool and similarly the air within the housing 5 is also relatively cool. The radiant heat in striking the diaphragm causes it to be heated above its surroundings and it thus buckles as set forth above to actuate the combustion switch. In some types of burners or in some installations the flame is somewhat unstable when the burner first starts, that is, the flame shifts in position. Thus at times, the radiant heat supply to the diaphragm falls off, and the diaphragm due to being surrounded by air which is cooler than itself, cools off to some extent, thus unbuckling slightly. Due to the action of the slip friction mechanism, this movement would tend to cause actuation of the combustion

switch even though no flame failure has occurred. Such action, however, is compensated for by the bimetal elements 22. When the burner first starts, these elements are in their cold positions. As the burner operates, the temperature in housing 5 gradually rises even though the flame may be unstable, this causing the elements 22 to progressively move the entire diaphragm assembly to the right as seen in Fig. 1. This movement continues while the combustion chamber is heating up and has the same effect on push rod 17 as buckling movement of the diaphragm. Thus when the diagram moves in unbuckling direction due to an unstable flame, this movement is compensated for by the progressive movement of the bimetal elements 22 and the push rod 17 remains stationary or may even continue to move to the right. As a result, unstable flame conditions occurring when the burner is first started are compensated for by the device and the combustion switch remains closed.

With some types of burners and under certain conditions, it is possible for the diaphragm to be heated up upon starting of the burner at a rate sufficiently greater than that of the ring, as to cause the diaphragm to unbuckle somewhat as equilibrium conditions are approached. This unequal rate of heating results from the ring having considerably more mass to be heated per unit of exposed area than the diaphragm. It will be apparent that due to both the diaphragm and ring being formed of expandable material, the degree of buckling of the diaphragm is partly determined by the difference in temperature between these elements. If the diaphragm reaches its maximum temperature while the ring is still relatively cool, the diaphragm will be buckled a greater amount than when the diaphragm and ring are at the same temperature. Thus under such conditions, the diaphragm will actually unbuckle while the ring is heating up, and the unbuckling might be sufficient to actuate the combustion switch, but for the action of the bimetal elements 22. It will be noted that these elements are rising in temperature at the same time that the diaphragm and ring are equalizing in temperature. Thus the movement of the diaphragm and ring by the bimetal elements counteracts such unbuckling movement of the diaphragm and the combustion switch remains in its "hot" position.

When the burner 81 is shut down or in the event of combustion failure during a running period, the flame 83 in the combustion chamber ceases to exist. The drop in temperature is immediately manifested upon the diaphragm 18 which senses the reversal or change in temperature and because of its thinness begins to move immediately toward a flat position, as shown in Fig. 1. This movement of the diaphragm 18 is passed to the shaft 17 by means of the shoulder 20 engaging the rear of the diaphragm. The shaft 17 causes levers 47 and 48 to rotate against the tension of spring 53. The initial movement of levers 47 and 48 causes the friction blade 55 to move the switch arm 60 into contact closing position away from stop screw 67. Continued inward buckling of the diaphragm 18 causes the friction blocks 56 to slip on the blade 55 after contacts 62 and 63 establish contact so that the mechanism can continue to move without straining the same. The bimetal blades 22 return slowly to their straight unwarped condition as shown at this time but do not prevent the immediate reverse action of the diaphragm.

In the event that the thermal responsive device 5 should develop a defect, burn off or become affected by any abnormal conditions the device is arranged to move into a "fail safe" position. That is, upon the automatic operation of the burner the device would operate under control of the tension spring 53 to cause opening of contacts 62 and 63 which would enable the burner 81 to start, but upon the automatic stoppage of the burner and the consequent extinguishment of the flame in the burner, the diaphragm or associated mechanism which is disabled would fail to restore the contacts to their closed position with the result that a lock out condition would occur in the burner circuit in the well known manner and prevent the further operation of the burner. The device therefore is arranged to provide for this "fail safe" feature in a simple and reliable manner.

It is contemplated in the present structure that the device may be utilized in a circuit arrangement in which the contacts 62 and 63 may be normally opened instead of closed as shown. This may be accomplished by simply reversing the position of the contacts and the adjusting stop screw 67. Under certain conditions an arrangement of this type is desirable and to produce a "fail safe" condition with this arrangement similar conditions would prevail as pointed out.

It is further contemplated that the unitary structure comprising the thermal responsive device 5 and the slip friction mechanism 6 be mounted in other positions than the top of the blast tube as illustrated in Fig. 6. For example it may be mounted on the side of the blast tube 10 or any other position. Under these conditions and that in which it is shown in Fig. 6 the sloped portion 13 on the casing 7 is arranged to intercept the radiant heat which emanates from the edge of the flame within the burner. This portion of the flame does not produce a stable condition but wavers considerably and if it were permitted to transmit its heat rays to the diaphragm 18 erratic operation may result. Therefore the opening 12 of the casing 5 is so arranged as to point toward the most intense or most stable portion of the flame in the combustion chamber and permit only the rays from this portion of the flame to pass to the diaphragm 18.

In Fig. 7 there is illustrated an adaptation of the combination thermal and switching mechanism for use in connection with a rotary or spinner type of burner. The motor for this burner is indicated generally at 84 and is suitably positioned in the bottom of a furnace casing 85 with the rotary spinner 86 positioned in the combustion chamber. The operation of the motor 84 results in the burning fuel being sprayed outwardly from the periphery of the disc 86 as indicated at 87. The thermal responsive unit 5 is positioned in the wall of the furnace casing 85 immediately below the flame 87 where the direct rays may affect the same. The unit is mounted within the casing by means of a sleeve member 88 to which it is attached by means of a set screw 89 engaging the supporting tube 16. A supporting plate 90 to which the sleeve 88 is suitably secured is carried by screws as shown upon a tubular enclosing member 91 extending from the outside of the furnace into the combustion chamber. The switching mechanism 6 is supported below the plate 90 as shown. The foregoing illustrates the adaptability of the control unit for mounting in various types of burners. The action and operation of the same in pro-

ducing the desired switching operations are similar in this arrangement as that described in connection with Fig. 6. However, since the flame 87 is propagated in a direction at right angles to the thermal responsive element 5 it is not necessary to provide a case such as at 7 in Fig. 1. The thermal element 5 is adjustably positioned by means of screw 89 closer or further away from the flame 87 as desired.

From the foregoing description it is perceived that an improved thermal responsive element is disclosed in combination with associated switching mechanism in which the mechanism is of simple construction, extremely reliable in operation and is arranged to safeguard its operation in a number of different instances. By combining the thermal element 5 and the switching mechanism 6 into a single unitary structure, a reduction in the wiring and installation costs is effected as well as a simplification of the testing, assembly and matching of the units. While the invention is illustrated in a preferred and modified form, it is contemplated that various modifications in the same may be made without departing from the spirit of the invention and it is therefore to be understood that the invention is not limited to the precise construction illustrated, but only by the scope of the appended claims.

What is claimed is:

1. In a thermostatic mechanism, the combination of a control device having a movable element, first thermal responsive means comprising two portions subjected to a variable temperature and arranged to change in temperature therewith at different rates, said thermal responsive means actuating said movable element, and a second thermal responsive means also subjected to said variable temperature and varying the movement of said movable element caused by said first mentioned thermal responsive means.

2. In a thermostatic mechanism, the combination of a control device having a movable element, first thermal responsive means comprising two portions subjected to a variable temperature and arranged to change in temperature therewith at different rates, said thermal responsive means actuating said movable element, and a second thermal responsive means also subjected to said variable temperature, said second thermal responsive means being arranged to oppose the effect of said first thermal responsive means caused by the different rates at which said two portions change in temperature.

3. In a thermostatic control mechanism, the combination of a control device having a movable element, thermal responsive means comprising two portions subjected to a variable temperature and arranged to change in temperature therewith at different rates, means including a slip friction device for transmitting reversals in motion of said thermal responsive means to said movable element, and a second thermal responsive means also subjected to said variable temperature, and influencing the actuation of said movable element by said first mentioned thermal responsive means.

4. In a thermostatic control apparatus, the combination of, a control mechanism comprising a control device and an actuator therefor including a slip friction mechanism, a thermal responsive means for causing movement of said actuator and hence said control device, said thermal responsive means comprising two portions subjected to a variable temperature and arranged to change in temperature therewith at

different rates whereby said thermal responsive means may reverse its initial movement following a change in said variable temperature due to equalization in temperature of the two portions, and means for substantially preventing such reversal in movement of said thermal responsive means from being transmitted to said actuator.

5. In a thermostatic control mechanism, the combination of a control device having a movable element, thermal responsive means comprising two portions subjected to variable temperature and arranged to change in temperature therewith at different rates, whereby said thermal responsive means may reverse its initial movement following a change in said variable temperature due to equalization of the temperatures of said two portions, a slip friction motion transmitting means for transmitting motion from said thermal responsive means to said movable element, and means for substantially preventing a reversal in motion of said thermal responsive means caused by the different rates of temperature change of said portions from being transmitted from said thermal responsive means to said slip friction motion transmitting means.

6. In a thermostatic control apparatus, the combination of, a control mechanism comprising a control device and an actuator therefor including a slip friction mechanism, a thermal responsive means for causing movement of said actuator and hence said control device, said thermal responsive means comprising two portions subjected to a variable temperature and arranged to change in temperature therewith at different rates whereby said thermal responsive means may reverse its initial movement following a change in said variable temperature due to equalization in temperature of the two portions, and means for substantially preventing such reversal in movement of said thermal responsive means from being transmitted to said actuator, said last mentioned means comprising a thermal responsive compensating device.

7. In a thermostatic control apparatus, the combination of, a control mechanism comprising a control device and an actuator therefor including a slip friction mechanism, a thermal responsive means for causing movement of said actuator and hence said control device, said thermal responsive means comprising two portions subjected to a variable temperature and arranged to change in temperature therewith at different rates whereby said thermal responsive means may reverse its initial movement following a change in said variable temperature due to equalization in temperature of the two portions, and means for substantially preventing such reversal in movement of said thermal responsive means from being transmitted to said actuator, said last mentioned means comprising a thermal responsive device also subjected to said variable temperature and arranged to change in temperature therewith at a relatively slow rate.

8. In a thermostatic control mechanism, the combination of, a control device having a movable element, thermal responsive means comprising two portions subjected to a variable temperature and arranged to change in temperature therewith at different rates, means including a slip friction device for transmitting reversals in motion of said thermal responsive means to said movable element, and a physical condition responsive device for cooperating with said thermal responsive means in positioning said actuator movable element.

9. In a thermostatic mechanism, the combination of a thermal responsive device formed of a relatively thin plate-like member adapted to change in temperature relatively rapidly, confining means for opposite edges of said member whereby said member buckles or unbuckles upon changes in a variable temperature to which the thermal responsive device is subjected, a control device having a movable element actuated by the thermal responsive device, and a second thermal responsive device subjected to said variable temperature for cooperating with said first thermal responsive device in positioning said movable element.
10. In a flame detecting device for fuel burners, the combination of, a control device, a relatively thin plate-like member for actuating said control device, said member being located in a region spaced from the flame and adapted to receive radiant heat from the flame, and means for preventing reversal in action of said member due to an unstable flame when the burner is first started, said means comprising a thermal responsive device which rises in temperature when the burner is placed in operation, movement of said thermal responsive device counteracting the effect of simultaneous movement of said member toward its cold position.
11. In a flame detecting device for fuel burners, the combination of, a housing having an open end and adapted to be aimed at the flame, the opening of the housing being of reduced cross sectional area as compared with the interior of the housing, a first thermal responsive device comprising a relatively thin plate-like member extending transversely of the housing and arranged to receive radiant heat passing through said opening, confining means for opposite edges of said member whereby said member buckles or unbuckles upon occurrence and discontinuance of said flame, a control device actuated by said member, and a second thermal responsive device for cooperating with said first thermal responsive device in positioning said control device.
12. In a flame detecting device for fuel burners, the combination of a housing having an open end and adapted to be aimed at the flame, the opening of the housing being of reduced cross sectional area as compared with the interior of the housing, a relatively thin plate-like member extending transversely of the housing and arranged to receive radiant heat passing through said opening, a control device, said member buckling and unbuckling upon presence or absence of flame for actuating said control device, and means for adjustably positioning said member at different distances from said opening to vary the amount of radiant heat received by said diaphragm.
13. In a control mechanism, a thermal responsive device comprising a diaphragm member and a ring member associated therewith, both of said members subjected to variable temperatures and arranged to respond thereto at different rates to actuate said control mechanism, and a second thermal responsive device comprising a bimetallic blade associated with said first thermal responsive device, said bimetallic blade arranged to respond to said variable temperatures at a different rate than said diaphragm and ring members to shift both of said members bodily from one position to another.
14. In a control mechanism, a thermal responsive device comprising a diaphragm member and a ring member arranged upon the periphery of said diaphragm member, said members subjected to variable temperatures and arranged to respond thereto at different rates, connecting means extending from one of said members to said control mechanism whereby the control mechanism is operated, and means for supporting said members, said supporting means comprising a bimetallic means subjected to said variable temperatures and arranged to respond thereto at a different rate than said members for bodily shifting said members.
15. In a control mechanism, a thermal responsive device comprising a diaphragm member and a ring member arranged upon the periphery of said diaphragm member, a connecting shaft extending from the center of said diaphragm member to said control mechanism whereby said control mechanism is operated when said members are subjected to variable temperatures, a supporting tube through which said connecting shaft extends, a plurality of bimetallic blades supported at one of their ends from said supporting tube and supporting the diaphragm and ring members from their other ends.
16. In a control mechanism, a thermal responsive device including a diaphragm member, a connecting shaft extending from the diaphragm member to said control mechanism for operating the same when the thermal responsive device is actuated in response to variable temperatures, a supporting tube through which said connecting shaft extends and having one end arranged adjacent said diaphragm member, a second thermal responsive device arranged upon the supporting tube end, said second thermal responsive device supporting said first thermal responsive device from the end of said supporting tube, and means arranged between the end of said supporting tube and said diaphragm member for closing the tube opening to prevent passage of air through said tube.
17. In a thermostatic control mechanism, the combination of, a control device having a movable element, thermal responsive means comprising two portions subjected to a variable temperature and arranged to change in temperature therewith at different rates, means including a slip friction device for transmitting reversals in motion of said thermal responsive means to said movable element, and a second thermal responsive means arranged to bodily shift said first thermal responsive means from one position to another.
18. In a thermostatic mechanism, the combination of, a thermal responsive device formed of a relatively thin plate-like member adapted to change in temperature relatively rapidly, confining means for opposite edges of said member adapted to change in temperature at a relatively slower rate whereby said member buckles or unbuckles upon changes in a variable temperature to which the thermal responsive device is subjected, a control device having a movable element actuated by the thermal responsive device, and a second thermal responsive device subjected to said variable temperature for bodily shifting said first thermal responsive device from one position to another.

CLIFFORD HOTCHKISS.
